CLAIM

The ornamental design for a partition plate of storage rack, as shown and described.

DESCRIPTION

FIG. 1 is a perspective view of a partition plate of storage rack showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is bottom plan view thereof.

FIG. 8 is a reference view of an embodiment of the present invention in a shelf configuration; and,

FIG. 9 is a reference view for another embodiment of the present invention.

The broken lines are for the purpose of illustrating the environment of the article only and form no part of the claimed design.
